SPRINKLER

Clarence P. Kramer, Chicago, Ill.

Application June 17, 1935, Serial No. 26,948

14 Claims. (Cl. 299—61)

This invention relates in general to a sprinkler and has more particular reference to that type of lawn sprinkler which is of the disappearing type having a sprayer head which automatically rises from a receptacle set into the ground, due to the pressure of water, and falls back by gravity, closing the receptacle when the water pressure is shut off.

An important object of the invention is in the provision of new and improved means for directing and guiding the spray discharged from a head of this kind but confining the spray at the desired limits and by tilting the sprayer head to direct the water at different elevations.

15 A further object of the invention is in the provision of a sprayer head having a number of holes which are controlled by an inside valve which is adjustable from the outside for changing a three-quarter-round sprayer at will either to a one-half or a one-quarter-round sprayer head.

A still further object of the invention is in the provision of an adjustable guard which is slightly curled, which has the effect of keeping the sprayed water in a straight line as far as possible from the head.

25 A still further object of the invention is in the provision of a removable screen within the sprayer head which can be easily removed for cleaning purposes without disturbing the setting of the head.

Other objects of the invention will appear hereinafter, the accompanying drawing illustrating a preferred embodiment of the invention, in which,

35 Fig. 1 is a sectional view of the sprinkler in closed position;

Fig. 2 is a view partly in section and partly in elevation showing the sprinkler head in raised or sprinkling position;

Fig. 3 is a section taken on the line 3—3 of Fig. 1;

Fig. 4 is an enlarged view of the adjustable guard;

Fig. 5 is a section taken on the line 5—5 of Fig. 1;

45 Fig. 6 is a sectional view illustrating the head in inclined position; and

Fig. 7 is a diagrammatic view showing the use of a sprinkler for different spraying areas.

In using a sprinkler head of this kind it is frequently desired to restrict the area covered by the nozzles to a half, a quarter, or even less, of the area covered by a full sprinkler head with nozzles all around, and it is furthermore desirable to vary the throw of the spray in any of the full-round or less than full-round nozzles,

which may be used. By full-round is meant the provision of discharge holes entirely around the head so that the spray will be discharged in all directions. The present invention is designed and intended to provide for the tilting of a full-round head to direct and to vary the spray as desired from it, and it is also to provide improved means for confining the spray from less than a full-round head by means of a valve on the inside and by means of adjustable guard plates on the outside.

Referring now more particularly to the drawing, a sprinkler head casing 10 is connected at its lower end to a water supply pipe 11 and the top of the casing is usually set at or just below the level of the ground which it is intended to sprinkle. At the lower end of the casing is a restricted bore 12 through which a hollow shell 13 extends loosely having a flange 14 at its lower end for restricting the upward movement and 10 for closing the bore 12. The upper end of the shell 13 is threaded into a fitting 15 externally threaded to receive a plate 16 with projections 17 engaging longitudinal grooves 18 in the casing 15 to prevent rotation of the fitting.

In the upper end of the fitting 15 is a round or spherical seat 19 for engaging a ball fitting 20 which is held thereon and in any adjusted position by a threaded gland 21 which engages the outer surface of the fitting 20 for holding it 20 inclined and in any adjusted position, as shown more clearly in Fig. 6. Pivoted to opposite sides of the gland 21 are arms 22 of a closure plate 23 which fits loosely within and closes the end of the casing 10. This closure plate has a weight 24 at one side which causes it to drop as shown in Fig. 2, to uncover the spraying head when it is in operation.

Extending from the ball fitting 20 is an integral, externally threaded sleeve 25 with spraying perforations or nozzles 26 at the base of the sleeve inclined to discharge water from the inside of the ball fitting in an upward and outward direction. Loosely adjustable on the outside of the sleeve 25 is a spraying guard 27 having a lower 40 inclined surface 28 for guiding the water from the spraying nozzles 26.

For full-round spraying heads this guard 27 is all that may be needed for discharging the water in a circular path, and the ball fitting 20 may 50 be variously inclined to raise or lower the spray line as desired.

For less than full-round spraying an adjustable guard plate has a ring portion 30 which is engaged by a clamping ring 31 threaded on the 55

hollow sleeve 25 and held by the clamping ring against the adjacent shoulder of the ball fitting 20 and has spaced vanes 32 held away from the inclined surface 28 of the spray guard 27 to provide a thin curved space between each vane 32 and the adjacent surface of guard 28. Each vane 32 preferably embraces the space covered by one of the nozzle openings 26 and each space between the vanes contains an opening 26. One or more of the vanes has a downwardly turned guide edge 33 at one side thereof so that the water striking this vane and against the edge 33 is confined in a straight line therefrom so that the lateral edge of the spray can be accurately determined and directed, as along the edge of a sidewalk. The guard 27 is also provided with a spray plate 34 adapted to project between the vanes 32 and below the guard 27 so that it may be adjusted with respect to the guard plate 33 to confine the spray from the openings in an arc between the guards 33 and 34.

Thus the spray from adjacent openings 26 is directed in different thin paths which do not intersect and produce a joint meeting place; for the spray from one opening 26 will engage a vane 32, and the spray from the next opening 26 on either side will engage the guard surface 28 and the edges of the arc of this spray will pass between the vanes 32 and the guard surface 28, out of the path of that spray which engages either of the vanes 32, and there will be no interfering contact between the edges of the sprays.

To restrict the spraying arc requires that a valve 35 is provided at the inside of the ball fitting 20 adapted to cover substantially one-half of the nozzle openings 26 within the fitting and having a stem 36 which extends outwardly beyond the end of the sleeve 25 where it is provided with a restraining washer 37 and a cotter pin 38 at the outer end of the stem and with a coil spring 39 surrounding the stem and bearing at one end against the under side of the washer 37 and at the other end against the end of the sleeve 25. The spring holds the valve 35 in any position in which it is set and the valve may be adjusted to cover more or less of the discharge openings 26 which can easily be seen by removing the ball fitting 20 and looking at the under side thereof as in Fig. 5, the exposed openings 26 having the limiting guards 33 and 34 for any adjustment thereof.

Thus it will be seen that for less than a full rotary sprayer a sprayer head comprises approximately three-quarters of the sprayer openings required for a full-head, the valve 35 covers approximately one-half of the circumference, and by the adjustments thereof it can be set to uncover any desired number of sprayer openings up to substantially a one-half round sprayer.

By correspondingly adjusting the side guard plates 33 and 34 the limiting edges of the spray are accurately defined, thus preventing wastage of water and the wetting of surfaces which do not require watering. It will furthermore be seen that the adjustment of the spraying openings for less than full-round spraying operations is entirely independent of the inclination of the sprayer head so that one can be effected without the other or both may be utilized for the most efficient spraying or sprinkling operation.

At the upper end of the pipe 13 within the fitting 15 a strainer 50 is seated, which may be flat or conical as shown, and it is easily removable for repair or replacement by simply removing the gland 21 and the fitting 20.

In the diagram shown by Fig. 7, a sprayer head 40 may be set for a half-round spray 41 against one edge of a wall 42; a one-quarter sprayer 43 with a full distance spray 44 may be set between the right angled side limits 45 and 46; and a sprayer head 47 may be so located that its spray outline 48 is less than the full spraying distance and may cover one-quarter or one-half of a reduced circle as shown. From this it is obvious that many variations of the spraying head may be made by simply varying the above described adjustable parts.

I claim:

1. A lawn sprinkler having a sprinkler head comprising a fitting with nozzle openings at the top, a guide carried by the fitting above the nozzle openings for causing a thin arcuate spray, valve means within the fitting for closing some of the openings and means carried by the fitting for limiting the side spray from the openings which are not closed.

2. In a lawn sprinkler, a sprinkler head comprising a fitting with a ring of upwardly inclined nozzle openings, a valve adjustable within the fitting for covering some of the openings, and adjustable means carried by the fitting at the outside and above the nozzle openings for limiting the upward and side spray from the nozzle openings not closed by the valve.

3. In a lawn sprinkler, a sprinkler head having a number of upwardly inclined nozzle openings, an inclined guard overlying the openings and carried by the sprinkler head, the guard being substantially in line with spray from the openings to limit its upward spreading, a valve within the sprinkler head adjustable to close some of the openings, a vanned spray plate for alternate openings between the guard and the head having a downwardly projecting limiting guide edge for engaging the spray from its adjacent nozzle opening and confining it in a straight line.

4. In a lawn sprinkler, a spraying head comprising a hollow fitting having openings extending upwardly and outwardly and a threaded stem extending centrally therefrom, a guard mounted on the stem and having a lower inclined surface for limiting the upward spray from the openings, a guide plate extending downwardly from this guard between the openings to limit the spray from adjacent openings to a straight line, a valve adjustable within the fitting for closing some openings leaving others open, and a vanned guard for alternate openings adjustable between the other guard member and the openings of the fitting having a downwardly turned guide at the edge of the vane for limiting the spray from another opening so that the spraying arc can be controlled and limited by the valve and said guide plate and the downwardly turned guide edge of the vanned guard.

5. A lawn sprinkler structure in accordance with claim 4, in which the sprayer fitting has a spherical outside surface, and an adjustable confining gland therefor to adjust the inclination of the fitting and thereby to vary the arc and inclination of the spray from the nozzle openings thereof.

6. In a sprinkler, a sprinkler head having a plurality of openings from which the spray would normally intersect, and means forming adjustable and differently disposed guide surfaces for the openings to direct and separate the spray from adjacent openings in similar non-intersecting paths the discharge from alternate openings

engaging one surface and the discharge from the remaining openings engaging another surface.

7. In a sprinkler, a sprinkler head having spraying openings, a guide having a surface for engaging spray from the openings and another guide with vanes for engaging spray from alternate openings with surfaces substantially parallel with the first guide surface and spaced from the first guide so that spray from the openings between the vanes passes between the guides.

8. In a sprinkler head according to claim 7, an end guide on each of the said other guides extending across the space between them and adjustable for varying and limiting the combined arc of spray of the openings and for defining an accurate end spray limit at each end of the arc.

9. In a sprinkler according to claim 7, an adjustable valve within the sprinkler head for determining the openings from which the spray will issue and thereby varying the arc of the combined spray from the nozzles.

10. In a sprinkler according to claim 7, means on and adjustable with and between the said guides for limiting the combined arc of spray which issues from the spray openings, and valve means within the head adjustable to control the openings through which the spray issues.

11. In a lawn sprinkler, a sprayer head comprising a ball fitting having a confining gland for adjusting and holding it in different angular positions, the ball fitting having a number of spraying openings, and means carried by the fitting operable from the outer end of the head for adjustably controlling the number of openings which are operative for spraying purposes and other adjustable means for limiting the spray in an upward and lateral direction.

12. In a sprinkler, a sprinkler head comprising a ball and a socket joint having an end fitting with a spherical seat, a hollow ball fitting adjustably on the seat at various angular inclinations, the ball having a ring of nozzles at its upper end, and a gland ring engaging the socket member and binding the ball in place thereon, and a guard carried by the ball fitting and overlying the nozzles with a lower inclined surface to limit and direct spray from them in an outward and upward direction.

13. In a sprinkler, a sprinkler head comprising a ball and socket joint in which the ball member is a hollow fitting having a ring of upwardly inclined nozzle discharge openings for spraying in different radial directions, a valve on the inside of the ball fitting adjustable to cover some of the nozzle openings, allowing fluid discharge from the others, and the ball fitting having a hollow stem through which the valve extends outside of the joint and through which it is adjusted, the socket member of the joint having a circular opening for limiting the angular adjustment of the stem and the inclination of the ball fitting therein.

14. In a sprinkler, a ball fitting having a hollow stem and a ring of discharge nozzle openings in the ball at the base of the stem, a valve within the ball fitting adjustable to cover some of the openings leaving the others open for discharge, having an adjusting stem which extends through the hollow stem, and holding means connected to the valve and hollow stem for retaining the valve in any adjusted position with respect to the openings.

CLARENCE P. KRAMER.
